UNITED STATES PATENT OFFICE

105,179

DESIGN FOR A TIRE

Henry G. Noss, Port Washington, N. Y., assignor to United States Rubber Products, Inc., New York, N. Y., a corporation of Delaware

Application January 7, 1937, Serial No. 66,932

Term of patent 7 years

To all whom it may concern:

Be it known that I, Henry G. Noss, a citizen of the United States of America, residing at Port Washington, county of Nassau, State of New York, have invented a new, original, and ornamental Design for a Tire, of which the following is a specification, reference being had to the accompanying drawing, forming part thereof, in which:—

Fig. 1 is a perspective view of a portion of a tire showing my new design;

Fig. 2 is a plan view thereof; and

Fig. 3 is a sectional view, taken along the section line III—III of Fig. 2.

I claim:

The ornamental design for a tire, as shown.

HENRY G. NOSS.
